DESIGN FOR A COAT

Jacob A. Silverman, New York, N. Y.

Application September 15, 1938, Serial No. 79,910

Term of patent 3½ years

To all whom it may concern:

Be it known that I, Jacob A. Silverman, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The characteristic feature of my design resides in the combination on the specific coat disclosed of the high military collar which extends out of the wide lapel in association with the curved princess seams and the stitched border on the coat front and the specific box pleat extending from the yokes to the waistline on the back as shown.

I claim:

The ornamental design for a coat, substantially as shown and described.

JACOB A. SILVERMAN.
